Specification of Letters Patent.

Patented Oct. 7, 1913.

Application filed June 15, 1912. Serial No. 703,521.

To all whom it may concern:

Be it known that I, HENRY H. VOUGHT, Jr., a citizen of the United States, residing in Bronxwood Park, Williamsbridge, New York, have invented a new and useful Improvement in Floor Construction, of which the following is a specification.

This invention relates to an improved hollow tile and concrete fire-proof floor of that type wherein the tiles or construction blocks are constructed and arranged to form T-channels, into which the concrete is poured and allowed to set in the form of T-beams having suitable interlocking engagement with the tiles.

The object of the invention is to provide a floor construction of this type embodying a two-way system of T-beams instead of a one-way system as heretofore. To this end the tile elements are arranged in rows and spaced apart both ways to present inverted T-formations in both elevations, so that a two-way system of crossing T-channels is produced, and a monolithic grafting-like concrete structure is formed in these channels so as to constitute a two-way system of concrete T-beams. By this construction economy in concrete is effected and the tops of the blocks are in compression. In the practical embodiment of the invention hereinafter described the tile blocks have lower projecting portions at their closed sides and complementary small blocks, corresponding to these projecting portions, placed against their open sides, so as to form the T-section in both directions.

A further object of the invention is to present an all-tile ceiling, that is to say, to cause the tiles to close the bottoms of the channels in which the T-beams are formed.

A still further object of the invention is to make use of the shouldered lower portions of the tiles or the complementary blocks to support means whereby the reinforcing rods extending longitudinally of the channels are spaced above the bottoms thereof uniformly and accurately.

A preferred and an alternative embodiment of the invention will now be briefly described, reference being had to the accompanying drawings wherein:

Figure 1 is an isometric perspective view of a portion of the preferred construction, parts being in section and broken away;

Fig. 2 is an isometric perspective view of one of the main blocks; Fig. 3 is an isometric perspective view of one of the complementary blocks; Fig. 4 is a view similar to Fig. 1, showing an alternative construction; Fig. 5 is an isometric perspective view of one of the main blocks employed in this construction; and Fig. 6 is an isometric perspective view of one of the complementary blocks shown in Fig. 4.

Reference will first be had to the construction shown in Figs. 1 to 3. Hollow tile blocks 10 are supported on suitable centering 11, which is subsequently removed. The blocks 10 are square on top and oblong at the bottom, having projecting portions 12 at the lower parts of their closed sides. These projections give the blocks an approximately inverted T-shaped formation when viewed from the open ends. A similar formation is afforded when the blocks are viewed from their closed sides by means of small complementary blocks 13, which are placed against their open ends. The blocks are arranged in rows running both ways and are spaced apart both ways so that two sets of crossing T-channels are produced. The narrow lower portions of these channels are formed in the one instance by the projecting portions 12, and in the other instance by the complementary blocks 13. By preference the opposed sides of the projecting portions 12 and the corresponding inner sides of the complementary blocks 13 are inclined or converge downward in a generally inclined relation and meet at the bottom, or the bases of the blocks are extended to meet, so that the bottoms of the T-channels are closed, thus retaining the concrete and giving an all-tile ceiling. As in the case of the complementary blocks 13^a of Figs. 4 and 6, the blocks 13 may be separate at the bottom, that is to say, there may be a pair of these complementary pieces between the open ends of each pair of main blocks 10, but preferably they are united at the bottom to form a trough-like double block as shown. Reinforcing rods 14 extend longitudinally of the T-channels, within the narrow lower portions thereof, and are spaced away from the bottoms by rod spacers 15, which are in the nature of hangers supported at opposite sides of the channels on the shoulders afforded by the projecting portions 12 and the

complementary blocks 13. The rods 14 are in crossing relation, one rod being slightly higher than the other at each cross-over, and the spacers are correspondingly proportioned. Concrete in a more or less fluid condition is poured into the T-channels and sets in the form of a monolithic grating, constituting a two-way system of T-beams. The tiles are provided with suitable dovetail or undercut locking grooves, with which the concrete engages. The covering layer 13 may be formed at the same time with the T-beams or subsequently.

15 The modified construction shown in Figs. 4 to 6 is similar to the preceding, except that the projecting portions 12^a of the tiles 10 have vertical faces and their bases do not meet, and that the complementary blocks 13^a likewise have vertical inner faces and are not united and do not meet at the bottom. Here the bottoms of the channel molds, in which the T-beam concrete structure is molded, are formed by any suitable form of centering, such as 11^a.

20 25 The complementary blocks 13 or 13^a are placed against the lower portions of the open ends or sides of the main blocks. The interiors of the latter are divided by partitions and the blocks 13 or 13^a close only the lower spaces. The concrete enters the upper spaces and thus forms a wide T as seen in the drawings.

What is claimed as new is:

30 35 1. A reinforced concrete and tile floor, comprising approximately hollow tile open ended blocks arranged in rows and spaced apart, the interiors of said blocks being divided by partitions into upper and lower spaces extending horizontally therethrough,

the closed sides of the blocks having their 40 lower portions projected, and complementary small blocks conforming to these projections placed against the lower portions of the open sides of the blocks and leaving said upper spaces open, whereby a two-way system 45 of crossing T-channels is formed, in combination with crossing concrete T-beams formed in said channels, the concrete extending into said upper spaces of the main blocks whereby a wide T is formed. 50

2. A reinforced concrete and tile floor comprising approximately tile blocks arranged in rows and spaced apart affording two sets of intersecting channels, the blocks being hollow with their openings extending 55 horizontally therethrough so that the blocks have open sides and closed sides, the lower portions of said closed sides projecting into the corresponding channels so as to narrow the lower parts thereof, complementary 60 small blocks spaced against the lower portions of the open sides in the other channels, said complementary blocks conforming to the projections of the closed sides and likewise narrowing the lower portions of their 65 channels, whereby a two-way system of T-channels is formed, and a two-way concrete T-beam structure formed in said channels, the tops of said complementary blocks and projections affording upward facing shoulders suitable for the reception of rod spacers. 70

In witness whereof, I have singed my hand this 12th day of June, 1912.
